Daniel Green Company, Dolgeville, N. Y.

Application September 15, 1949, Serial No. 5,003

Term of patent 7 years

(Cl. D7—7)

To all whom it may concern:

Be it known that I, Schuyler Wood, a citizen of the United States, residing at Dolgeville, in the county of Herkimer and State of New York, have invented a new, original, and ornamental Design for a Bedroom Slipper or Similar Article, of which the following is a specification, reference being had to the accompanying drawing, forming part thereof.

In the drawing

Fig. 1 is a side view of a bedroom slipper or similar article showing my new design;

Fig. 2 is a top plan view thereof; and

Fig. 3 is a rear view thereof.

The essential features of my design reside in the parts shown in full lines.

I claim:

The ornamental design for a bedroom slipper or similar article, substantially as shown and described.

SCHUYLER WOOD.
